UNITED STATES PATENT OFFICE

168,734

HANDBAG ORNAMENT OR SIMILAR ARTICLE

Louis J. Coblenz, New York, N. Y.

Application April 30, 1952, Serial No. 19,537

Term of patent 14 years

(Cl. D87—2)

To all whom it may concern:

Be it known that I, Louis J. Coblenz, a citizen of the United States of America, residing in New York city, county of New York, and State of New York, have invented a new, original, and ornamental Design for a Handbag Ornament or Similar Article, of which the following is a specification, reference being had to the accompanying drawing, forming part thereof.

Fig. 1 is a plan view of a handbag ornament or similar article, showing my new design.

Fig. 2 is an edge view thereof.

I claim:

The ornamental design for a handbag ornament or similar article, substantially as shown.

LOUIS J. COBLENTZ.
